UNITED STATES PATENT OFFICE.

ARTHUR ENGELBERG, OF OAKLAND, CALIFORNIA.

TELEPHONE RECEIVER AND RECEIVER-SWITCH.

1,337,892.

Specification of Letters Patent. Patented Apr. 20, 1920.

Application filed January 27, 1919. Serial No. 273,245.

To all whom it may concern:

Be it known that I, ARTHUR ENGELBERG, citizen of the United States, residing at Oakland, in the county of Alameda and State of California, have invented certain new and useful Improvements in Telephone Receivers and Receiver-Switches, of which the following is a specification.

My invention is an improved telephone receiver and receiver switch.

My improved receiver is shorter and lighter than the standard telephone receiver now in use, and may be connected with a shorter wire than is required by the standard receiver.

My invention is illustrated in the accompanying drawing which forms a part of this specification and the appended claims.

Referring to the drawing:

20 Figure 1 is a side elevation of a telephone embodying my invention, the standard of the telephone being broken away to show the receiver switch.

25 Fig. 2 is a rear view of the telephone as shown in Fig. 1, certain parts of the telephone being broken away, and the receiver switch being shown open or in the position it assumes when the receiver is on the hook.

Fig. 3 is a view corresponding to Fig. 2, 30 except that the receiver switch is shown closed or in the position it assumes when the receiver is removed from the hook.

Fig. 4 is a sectional view taken on line 4—4 of Fig. 1.

35 Fig. 5 is a sectional view taken on line 5—5 of Fig. 1.

Fig. 6 is a diagram of a telephone system illustrating my invention, the receiver switch being open.

40 Fig. 7 is a view similar to Fig. 6, the receiver switch being closed.

In the drawing, 1 indicates the stand, 2 the transmitter and 3 the receiver of a telephone, the stand including the base 4, tubular standard 5 and support 6, which fits within 45 and rests on the upper end of the standard in the usual manner. The transmitter is pivoted as usual at 7 to the upper end of the support 6.

50 A receiver hook 8 is fixed to the support 6. The hook is formed of a single strip of metal bent in the middle in the form of a loop 9 and upon itself from the loop to its ends. The loop 9 surrounds the shank 55 10 of the support 6 and is clamped thereon by a bolt 11, extending through the hook

just beyond the loop, and a nut 11' screwing on said bolt against the hook. The hook is notched at 12 in which an eye 13 on the top of the receiver is hooked to hold the receiver on the hook. The eye 13 is formed with a threaded shank 13' which extends through an aperture 14 in the top of the receiver and is hooked into an eye 49 of a brass band 50 which encircles the weight 60 connection 15', thus connecting the eye to the receiver weight 15 inside of the receiver.

65 The receiver cord 16 carrying the receiver leads 17 and 18 extends through the receiver aperture 14 in the usual manner.

70 A unique receiver switch 20 is provided for making or breaking the telephone circuit as the receiver is removed from or hung on the hook. The switch includes the usual spring contacts 21 and 22 and the 75 contact 23, a wedge 24, roller 25, rod 26 and lever 27. The wedge 24 is secured to the lower end of rod 26 which extends through a bore 28 through the support 6. The roller 25 is journaled in a bracket 29 secured to bar 30 forming part of support 75 80 6, and on which the contacts 21, 22 and 23 are mounted. The upper end of the rod 26 is reduced and threaded and extends through an eye 31 on the rear end of lever 85 27 and a shoulder 32 is formed on said rod at the base of said reduced end upon which said eye rests. The lever 27 is pivoted to the hook 8 by pivot 33, the pivot having an eye 34 through which the lever extends. 90

95 The pivot may be formed of a single piece of metal bent in the form of the eye 34 and upon itself, to extend through an opening 35 in the hook, and the ends bent outwardly to hold the pivot in one direction against axial movement, the pivot being held against axial movement in the other direction by eye 34. A light spring 36 connects to the lever 27 and to the support 6 and forces the rear end of the lever, and the rod 26 and wedge 24, downwardly when the receiver is removed from the hook, causing the wedge to enter between roller 25 and contact 21 and close the receiver switch as shown in Fig. 3. A nut 37 screws on the 100 upper reduced end of the rod 26. Upon placing the receiver upon the hook the weight of the receiver bears the forward end of the lever down and the rear end up which movement causes the eye 31 to 105 engage nut 37 and lift the rod 26 upwardly and the wedge 24 from the roller 25 and con-

tact 21, thus opening the receiver switch. Upon removing the receiver the spring 36 draws the rear end of lever 27 down and the forward end up, and the eye 31 engages 5 the shoulder 32 and forces the rod and wedge 24 into engagement with roller 25 and contact 21, thus closing the receiver switch.

The usual terminals R, GN and Y are 10 provided for connecting the telephone circuit.

The spring 36 may be very light so that the receiver and weight 15 may be reduced in length, thus reducing the weight of the 15 receiver and shortening the length of the receiver cord 16 which is necessary with the present standard receiver.

Parts of the rod 26 and lever 27, and the spring 36 may be inclosed by a metal casing 20 40 to prevent said parts from being injured.

The receiver is less than half the weight of the present one, the cord is considerably shorter than the one in use now, and cannot, therefore, catch on corners of desks, 25 twist out of shape, become soiled from necessary handling and cause accidents to the telephone instrument by being thrown to the floor and to objects lying or standing on desks, like inkstands, etc.

30 Another advantage of the invention is the noiseless working of it; there are many peo-

ple who become impatient if the operator does not at once answer their call; they work the receiver hook up and down repeatedly, causing thereby disagreeable 35 noises. This invention does not admit of such practice; it makes, at least, no noise if the end of the lever governing the contact is pressed down.

Having described my invention, I claim: 40

1. In a telephone, a fixed receiver hook and a receiver switch including contacts, a roller, a wedge, a rod to which said wedge is connected, a lever to be engaged by the receiver when on the hook and engaging 45 said rod to withdraw said wedge from between said roller and said contacts to open the switch when the receiver is on the hook, and a spring for swinging said lever to force said wedge between the roller and contacts 50 to close the receiver switch when the receiver is removed from the hook.

2. In a telephone, a fixed receiver hook, and a receiver switch including contacts, a roller, a wedge and means for forcing said 55 wedge between said roller and said contacts to close the switch when the receiver is off the hook and for withdrawing said wedge to open said switch when the receiver is placed on the hook. 60

In testimony whereof I affix my signature.
ARTHUR ENGELBERG.
